UNITED STATES PATENT OFFICE.

PAUL BROWN KLUGH, OF CHICAGO, ILLINOIS, ASSIGNOR TO THE CABLE COMPANY, OF CHICAGO, ILLINOIS, A CORPORATION OF ILLINOIS.

AUTOMATIC MUSICAL INSTRUMENT OR PLAYER.

No. 833,967.

Specification of Letters Patent.

Patented Oct. 23, 1906.

Application filed June 5, 1905. Serial No. 263,736.

To all whom it may concern:

Be it known that I, PAUL BROWN KLUGH, a citizen of the United States, residing at Chicago, in the county of Cook and State of Illinois, have invented new and useful Improvements in Automatic Musical Instruments or Players, of which the following is a specification, reference being had to the accompanying drawings, forming a part thereof.

This invention relates to the construction of automatic musical-instrument players, commonly called "piano-players," the purpose of the invention being to afford a more rigid construction than heretofore obtained for the case or framework and to utilize certain parts which are necessary to the operation of the mechanism for the secondary or incidental purpose of strengthening and stiffening the frame structure.

It consists of the features of construction set out in the claims.

In the drawings, Figure 1 is a fore-and-aft vertical section at the line 1 1 on Fig. 2 through a player having my improvements, parts of the mechanism not necessarily involved being omitted. Fig. 2 is a section at the line 2 2 on Fig. 1. Fig. 3 is a section at the line 3 3 on Fig. 1.

The case of this player comprises two end standards 1 1, which are strongly reinforced by fore-and-aft sills 2 2 across their lower ends; the front board 3, which comprises a sill 3^a, extending the entire length from end standard to end standard at the lower edge of the front board; the main back board 4, which is secured rigidly at its ends onto the rear edges of the end standards 1 and which is further secured, as hereinafter more particularly explained; the neck back board 5; the shoulder-board 6, and the several parts of the upper portion of the casing A, inclosing the pneumatic action, (not illustrated,) which is not particularly involved in the present invention. The sills 2 are made as rigid as possible with the remainder of the end standards 1, as by gluing and screws 1^a. To form a bottom over so much of the case as can be inclosed without impeding the pedal-action, bottom boards 7 7 are provided, which are secured at their ends to the sills 2 2, respectively, and at the forward side to the front sill 3^a, angle-irons 7^b and cleat-irons 7^c being employed to give the utmost rigidity to the junction of such bottom boards with the end sills, and cleat-irons 7^c being similarly employed for making them more se-

curely rigid with the front sill 3^a. These two bottom boards are separated by an interval at the middle of the length of the instrument in which the pedal movement for operating the pumpers and the movement of the lower end of the pumpers themselves may be accommodated.

9 is the wind-chest or air-chamber. This element of the player is made in the form shown, consisting of a flat chest which extends the entire length of the instrument from end standard to end standard and substantially the entire height of the instrument from the bottom sills to the shoulder-board 6. This flat chamber or box is set obliquely—that is, inclined from front to rear—and abuts at its two ends directly upon the end standards, being secured to them rigidly, so as to brace them firmly, as it is well calculated to do by its width being nearly the full height of the standards to their shoulders.

A thoroughly secure method of joining the ends of the chamber 9 to the end standards is that represented in the drawings, which consists in employing cleats 10 10, secured to the inner sides of the end standards, respectively, in front of the chamber 9, so that the latter, being lodged against the cleats and being secured to them, is joined very rigidly to the end standards without the necessity of using screws or other fastenings extending through the standard into the wind-chest and without any danger, therefore, arising from the mode of mounting or securing it, of rupturing the chamber, or causing it to leak. This long and flat chamber having mounted upon its rear side the pumpers 11 11 and the receiving or regulating bellows 14 14, the functions of which are well understood and need not be further explained, would be liable to spring at the middle under the action of the pumpers, which are necessarily mounted upon it at the middle part, and such springing would not only tend to diminish the rigidity of the case, but would also tend to spring leaks in the chamber. To prevent such result and by stiffening the chamber not only secure its safety, but adapt it to increase the stiffness of the case as a whole, I provide the metal chairs or cross-ties 12 and 13 at the bottom and top, respectively, of the chamber. The chair 12 at the bottom is secured rigidly at the forward end to the front sill 3^a at the middle of the length of the latter, which brings it between the

pedals and in position which does not interfere with their action or that of their connections to the pumpers.

The chair is bent to form a seat at 12^a for the lower end of the chamber 9, which is thus embraced at its lower edge in such seat and held, against deflection either rearward or forward. The chair is deflected downward from the rear side of the wind-chest 9 and extends under a rear sill 4^a, which is provided as a reinforce for the lower edge of the back board 4, to which such sill is rigidly secured, and the chair-iron has an upbent end 12^b behind the back board, secured by screws taking into the back board and into the sill 4^a. This construction connecting the front sill 3^a and rear sill or reinforce 4^a and the lower edge of the chamber 9 at the middle of the length of the three parts causes each of said parts to reinforce the other against back or forward springing or deflection and causes them all to contribute their stiffness to resist such springing as might otherwise result from the action of the pumpers on the chamber 9. The front board 3 is reinforced by the wide stiffener or reinforcing-board 3^b, which is glued and screwed fast to the rear side of said front board above the pedal-opening and is rabbeted at 3^c at its lower edge to form an upper slide-track for the pedal-doors D. The upper tie-bar of chair 13 is secured rigidly at its forward end to the front board 3, being lodged upon and bolted to the upper edge of the reinforce-board 3^b and at its rear end to the back board 4, being intermediately extended directly rearward from the reinforce-board to the wind-chest, along whose front forward side it then extends upward to the upper edge and across said edge to the rear and then downward, forming a seat or recess 13^a, engaging the upper edge of the wind-chest. The case thus comprises, for the purpose of stiffening it in vertical longitudinal planes, front board, back board, and the wind-chest, each of which is rigid at the ends with the end standard, and for stiffening it in horizontal longitudinal plane it has bottom boards 7 7, which are rigid with the end standards and with the front sill in the angle between them. On the inner ends of the bottom boards 7 7 there are mounted and rigidly secured to the latter chair-blocks 7^d 7^d, which afford lodgment for the lower edge of the wind-chest 9 and which may be notched to receive said edge, thus, in addition to the metal chair 12, serving to prevent springing of said edge of the wind-chest. The wind-chest is also rabbeted at the lower corners to fit the sills 2 2, and thus obtains lodgment thereon at 9^a. (See Fig. 1.)

I claim—

1. In an automatic player for a musical instrument, in combination with end standards for supporting the mechanism, a flat air-chamber or wind-chest which extends

from one of the end standards to the other, and which abuts at its ends on the respective standards over the greater part of their height, and which is rigidly secured to such end standards at said abutting ends.

2. In an automatic musical instrument or player, in combination with the end standards, front and rear foot-sills connecting the standards; a wind-chest attached at its ends to the end standards, and a tie-bar intermediate the ends of the instrument rigidly connecting the front and rear sills and engaged with the lower edge of the air-chamber.

3. In an automatic musical instrument or player, in combination with the end standards, front and back boards rigidly joined at their ends to the end standards; a flat air-chamber or wind-chest which extends from one end standard to the other and abuts at its ends on the respective standards over the greater part of the height of each and is rigidly secured thereto, and a tie-bar secured intermediate the ends of the front and back boards to said boards, respectively, and intermediately engaged with the upper edge of the air-chamber.

4. In an automatic musical instrument or player, in combination with the end standards and front and rear foot-sills, a bottom structure comprising two bottom boards at the opposite end portions, respectively, of the case, joined rigidly to the respective end standards and to the foot-sills, such bottom boards being separated at their proximate ends by an interval for accommodating the pedal-action, and a tie-bar rigidly connecting the front and rear sills in such interval.

5. In an automatic musical instrument or player, in combination with the end standards, a flat air-chamber or wind-chest which extends from one end standard to the other and abuts at its ends on the respective standards over the greater part of the height of each and is rigidly secured thereto; front and rear inclosing elements of the case and tie-bars joined rigidly at their front and rear ends to such front and rear case elements respectively, intermediate the ends of the instrument, and engaged, respectively, intermediate their ends with the upper and lower edges of the air-chamber.

6. In an automatic musical instrument or player, in combination with end standards, a flat air-chamber or wind-chest connected at its ends to the end standards; a bottom structure connecting the lower ends of the standards and comprising bottom boards with space for the pedals between them and chair-blocks for the lower edge of the wind-chest mounted on the bottom boards at opposite sides of the pedals.

7. In an automatic musical instrument or player, a front board apertured at its lower part for the pedals; a reinforce-board secured to the rear or inner surface of the front board

extending along the upper side of the aperture, the rear board and a brace or tie-bar connecting the front and rear board secured to said reinforce for the forward connection.

5. 8. In an automatic musical instrument or player, in combination with the front board apertured at the lower part for the pedals, slides for closing the pedal-aperture and a reinforce-board secured to the rear or inner 45 face of the front board along the upper margin of the pedal-aperture and having its lower edge provided with a slide-track or guideway for the upper edge of the slides.

9. In an automatic musical instrument or 50 player, in combination with the end standards, front and back boards rigidly joined at their ends to the end standards, the air-chamber or wind-chest extending from standard to standard, the front board being apertured 55 for the pedals; a reinforce-board which extends along the upper margin of the aperture secured to the rear surface of the front board; a brace or tie-bar which connects the front and back boards and intermediately engages 60 the wind-chest, said brace or tie-bar having its forward ends connected to the front board by attachment to said reinforce.

10. In an automatic player for a musical instrument a portion terminating in an upwardly-facing shoulder adapted to extend 65 under the manual breast of the instrument to be played, in combination with end standards, a flat air-chamber or wind-chest which extends from one end standard to the other and abuts at its ends on the respective standards substantially from said shoulder down to the foot, and which is rigidly secured to such end standards at said abutting ends.

35 11. In an automatic player for a musical 70 instrument an upwardly - facing shoulder

adapted to extend under the manual breast of the instrument to be played, in combination with end standards, front and back boards rigidly joined at their ends to the end standards; a flat air-chamber or a wind-chest 45 which extends from one end standard to the other and abuts at its ends on the respective standards substantially from the shoulder to the foot of each, and which is rigidly secured to said standards at said ends, and a tie-bar 50 secured intermediate the ends of the foot and back boards to said boards respectively and intermediately engaged with the upper edge of the air-chamber.

12. In an automatic player for a musical 55 instrument an upwardly - facing shoulder adapted to extend under the manual breast of the instrument to be played, in combination with the end standards, a flat air-chamber or wind-chest which extends from one 60 end standard to the other and abuts at its ends on the respective standards substantially from the shoulder to the foot of each and is rigidly secured thereto; front and rear 65 inclosing elements of the case, and tie-bars rigidly joined at their front and rear ends to such front and rear case elements respectively intermediate the ends of the instrument and engaged respectively intermediate 70 their ends with the upper and lower edges of the air-chamber.

In testimony whereof I have hereunto set my hand, in the presence of two witnesses, at Chicago, Illinois, this 22d day of May, A. D. 1905.

PAUL BROWN KLUGH.
